SAFETY RAZOR WITH SEPARABLE CAP

Jose C. Ferrer, Santurce, Puerto Rico

Application December 6, 1954, Serial No. 473,382

1 Claim. (Cl. 30—53)

This invention relates to safety razors in which the blade cutting edge is parallel to the handle of the razor.

The objects of the invention are to construct a safety razor in which the cutting edge of the blade is parallel to the handle of the razor, and which is secured in place by a readily removable cover.

In general, these objects are obtained by providing a blade holding support attached to a handle, said support having a rib for receiving a centrally slotted safety razor blade and which rib also positions a blade cover and secures one end of the cover. The opposite end of the cover is releasably secured by a slidable collar. The blade support is curved so that the blade is held under tension on the razor. When the collar is retracted, the blade will spring back into normal flat position, and in so doing will push the blade cover off the razor, thus completely freeing the blade.

The means by which the objects of the invention are obtained are disclosed more fully with respect to the accompanying drawings, in which:

Figure 1 is a plan view of the razor;

Figure 2 is an enlarged cross-sectional view on the line 2—2 of Figure 1;

Figure 3 is an enlarged cross-sectional view on the line 3—3 of Figure 1; and

Figure 4 is a plan view of the blade cover separated from the razor.

The razor is composed of a handle A which may have an extension piece illustrated in Figure 1. Handle A is formed of an upper piece 2 and a lower piece 4 braised or welded together. Lower piece 4, adjacent the end of the razor, has a projecting stop shoulder 5.

Secured to the handle A, as an extension of piece 2, is a widened blade supporting member 6. This member has a concave undersurface 8, and a corresponding convex upper surface 10. Support 6 is wider than the razor blade, being extended by a reduced flange portion 12 on each side thereof containing cleaning slots 13. Flanges 12 extend under the outer edge of the razor blade to shoulders 14, thus permitting free clearance for the cutting edge of the razor blade. Axially mounted on the upper surface 10 of the support 6 is a rib 16, which longitudinally stops short of the ends of supports 6. The support end 18 of rib 16 is undercut to form a beveled surface, whereas the rearward end 20 of rib 16 is in a flat vertical plane. Between support 6 and handle A is a slightly flattened con-

2

necting section 22, around which is a slidable metal band or collar 24. As shown in Figure 3, this collar is formed of a strip of springy metal, the free ends of which are slightly spaced so that the collar can be resiliently engaged in a wedging action upon a tongue as will be described later.

Cover member 30 has a curvature of such thickness that when assembled on the support with blade 40, the top surface of cover 30 is flush with the top surface of rib 16. Cover 30 is centrally slotted for a length equal to that of rib 16, and at the forward edge of the slot is a beveled surface 34, which is complementary to end 18 of rib 16. The rear end 36 of slot 32 is vertical to conform with rear end 20 on rib 16. Cover 30 is provided with a rearwardly projecting tongue 38 which is slightly downwardly tapered and outwardly convergent, as shown in Figures 2 and 4. It has a thickness such as can be tightly held by slidable collar 24, as shown in Figure 2.

In operation, assuming the razor is disassembled, an ordinary centrally slotted double-edged safety razor blade is placed over rib 16 and is seated on support 6. Cover 30 is then placed in position by placing slot 32 over rib 16 and sliding the cover rearwardly so that surfaces 18 and 34 are lockingly engaged and end 20 is abutted by end 26. Collar 24 is then slid forwardly up over tongue 38, and with a wedging action holds cover 30 tightly in place. In so assembling the razor, the razor blade is held under tension in a downwardly curved direction with the cutting edges of the blade extending slightly beyond the longitudinal edges of cover 30. The razor is then ready for use. When the razor is disassembled, collar 24 is moved rearwardly, the extent of movement being limited by abutment 5, and as the edge of collar 24 clears the tongue 38, the tension in blade 40 will cause the blade to straighten out and thus push cover 30 upwardly off the rib 16. This action is automatic and disassembles the pieces so that they can be cleaned and dried and made ready for further use.

Having now described the means by which the objects of the invention are obtained, I claim:

A safety razor comprising a blade support, a handle attached to said support, a rib extending longitudinally of said support for positioning a centrally slotted double edge razor blade, an undercut in the forward end of said rib, a centrally slotted cover fitted over said rib, said cover and support having curved blade engaging surfaces adapted to hold a razor blade under tension, a beveled surface at one end of the slot in said cover complementary and mated to the undercut end of said rib, a tongue on said cover extending over said handle, and a collar on said handle slidably engaging said tongue.
